UNITED STATES PATENT OFFICE.

FREDERICK T. RUSSELL AND MILTON M. FAVOR, OF GARDNER, MASSACHUSETTS.

DESIGN FOR A DOOR-STOP BASE OR FRAME.

SPECIFICATION forming part of Design No. 32,109, dated January 16, 1900.

Application filed January 27, 1899. Serial No. 703,616. Term of patent 3½ years.

To all whom it may concern:

Be it known that we, FREDERICK T. RUSSELL and MILTON M. FAVOR, of Gardner, in the county of Worcester and State of Massachusetts, have invented and produced a new and original Design for Door-Stop Bases or Frames, of which the following is a description.

The accompanying drawing forms an essential part hereof and shows our new and original design for a door-stop base or frame in perspective.

As shown in the accompanying drawing, the leading or material features of our design consist of the cylindrical form of the body *a*, the square form of the base *f*, and the straight-

edged and smooth-sided web *e*, extending at a right angle from the plane of the base *f* to the side of the cylindrical body *a*.

Having described our invention, we declare ²⁰ that what we claim is—

The design for a door-stop base or frame as herein shown and described.

In testimony whereof we have signed our names to this specification, in the presence ²⁵ of two subscribing witnesses, this 25th day of July, A. D. 1898.

FREDERICK T. RUSSELL.
MILTON M. FAVOR.
